(57) **CLAIM**

The ornamental design for the ring, as shown and described.

DESCRIPTION

FIG. 1 is a perspective view of the ring showing my new design.

FIG. 2 is a front elevational view thereof;

FIG. 3 is a back elevational view thereof;

FIG. 4 is a side elevational view thereof, an opposite side, top and bottom views being identical to the side view; and,

FIG. 5 is another upper perspective view thereof, showing a size adjustment position of the inner diameter.
